UNITED STATES PATENT OFFICE.

LOUIS B. SMYSER, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

TRANSOM-OPERATOR.

1,093,296.

Specification of Letters Patent. Patented Apr. 14, 1914.

Application filed March 13, 1913. Serial No. 753,953.

To all whom it may concern:

Be it known that I, LOUIS B. SMYSER, a citizen of the United States, residing at New Britain, Hartford county, State of Connecticut, have invented certain new and useful Improvements in Transom-Operators, of which the following is a full, clear, and exact description.

This invention relates to operating means for transoms and allied closures, and is designed to provide a device of this character with a relative arrangement of parts affording greatest operating power at the period of greatest load; to provide an assembled operating unit ready for attachment; and further, to provide improved features of construction in connection with the operating mechanism. These and other advantages will be more fully described in the following detailed specification taken in connection with the accompanying drawings forming part thereof and illustrating a preferable embodiment of the invention.

In these drawings: Figure 1 is a fragmentary view in side elevation from the outer face of a door jamb showing the operating mechanism applied thereto and connected to a transom. Fig. 2 is a front elevation, partly in section, of the parts shown in Fig. 1. Fig. 3 is a fragmentary view in side elevation on an enlarged scale, of the parts shown in Fig. 1 with the transom and its operating parts in closed position. Figs. 4 to 7 inclusive are views on an enlarged scale of details of construction of the operating mechanism. Fig. 8 is a view in elevation and on an enlarged scale of the transom operating bar and gear case. Fig. 9 is an end elevation of the same partly in section. Fig. 10 is a view in elevation of the transom operating bar and gear case, the latter broken away and in section to disclose the interior arrangement. Figs. 11 and 12 are views of details of construction of the gearing. Fig. 13 is a sectional view through a door casing illustrating the position of the frame and gear casing therein.

As I have before stated, one of the objects of the present invention is to provide a unit construction whereby the operating parts may be applied as an assembled unit. These operating parts, or such as are capable of assembly prior to the application thereof to a door casing, are to be mounted on a frame or carrier preferably in the form of a metal

bar or plate 1 extending vertically of the door edge and applied to the outer face of the door jamb 2, or to that face which is non-adjacent the door.

3 designates a transom of the bottom hinged type, the hinging means being designated at 4. The end face of this transom at a point intermediate its top and bottom is provided with a plate 5 fixedly secured thereto and provided with a longitudinal slot 6.

7 designates a transom arm having a stud 8 at its upper end seating in the slot 6 of the transom plate. The lower end of this arm is provided with two or more segmental slots 9 therein. This arm 7 is located on the transom and door side of the jamb 2. On the opposite or outside face of the jamb is located a second arm 10 having a stud 11 secured to one end and carrying an anti-friction roller 12, and at its opposite end provided with segmental slots 13. The frame 1 and jamb 2 are bored to provide an opening through which a connecting stud 14 for these two arms 7 and 10 may extend, this stud being provided at its opposite ends with segmental projections 15 designed to fit into the segmental apertures 9 and 13 in these arms to rigidly connect them together. The arms are locked by means of a screw extending through a longitudinal bore in the stud and threaded into the arm 10 between its slots 13. The head of the screw seats in a countersunk recess in the arm 7 between its slots 9. These arms are connected at an acute angle and together form a lever designed, when force is applied to the free end of the arm 10 thereof, to move the transom 3 into and out of closed position. These operating parts for the transom which I have described are separate from the frame 1 carrying the operating mechanism and are attached to the transom independently thereof, the door jamb, of course, being provided with a bore through which the stud 14 extends, and a bushing 16 being preferably provided in this bore. The frame 1 is provided with an aperture therein through which the bushing and stud may extend, the length of these parts being such as to space the face of the arm 10 from the face of the frame 1.

The operating unit, of which the plate 1 forms the bed or frame, is designed as follows: A plurality of spaced and alined

brackets 17 are provided, these brackets being rigidly secured to the frame 1 by any suitable means and being apertured to guide therethrough an operating bar 18 extending vertically of the door jamb and longitudinally of the frame 1. Adjacent its upper end, this operating bar has fixedly attached thereto a sleeve 19. Adjacent its upper end, the frame 1 carries a bell-crank lever 20, one end being pivotally mounted on said frame by suitable means as by a stove bolt 21, or similar means, which may extend through an aperture formed in the frame 1 and through a bore in the door jamb 2, thus serving also to connect the upper end of the frame to the door jamb, although other or additional means may be employed to effect this result, if desired. 22 designates a link pivotally connecting the other end of the bell-crank to the fixed sleeve 19 of the operating bar 18. This bell-crank is designed to operate the transom through the arm 10 connected thereto. As shown, the bell crank is provided with an elongated slot 23 therein, this slot extending between the pivot point 21 of the bell-crank and the apex of its angle. A strengthening boss 24 is preferably formed about this slot. The anti-friction roller 12 of the arm 10 is designed to rest within the slot, the arm 10 being mounted to position its roller at the lower end of this slot when the transom is in its lowered position so as to afford maximum leverage through the bell-crank lever 20 to raise the transom to closed from opened position, this maximum leverage being available at the time of maximum load or when the transom has been opened.

It will be evident that by moving the operating bar upwardly and downwardly, the bell-crank 20 will be swung on its pivot to swing the transom to and from closed position through the connecting lever formed by the arms 7 and 10 and pivoted eccentrically relative to the bell-crank so that the movement of the bell-crank on its pivot will swing this lever to effect the result named. In order to move this operating bar 18, its lower end is formed as a rack 25 and a gear 50 casing 26 is provided through which this rack end of the bar is guided, this gear case being secured to the frame 1 by means of stove bolts 27 which extend through apertures formed in the frame 1 and through 55 bores formed in the door jamb 2, and serve also to connect the lower end of the frame 1 to the jamb. These bolts extend out of and are accessible from the door side of the jamb, as will be clearly seen from the 60 drawings. The gear casing is provided with a cover 28 including gear housings 29 and 30. A rack-engaging gear wheel 31 is seated in the base of the gear casing and is provided with an integral sleeve 32 and 65 with bosses 33 formed at opposite ends of

this sleeve and gear wheel by means of which this gear element is journaled in the gear case. The sleeve portion 32 of this gear element, intermediate its ends, is formed with an annular worm gear 34 70 thereon, and is also provided with a central bore 35 having a by-pass connection 36 with this annular gear 34 for the purpose of transmitting a lubricant thereto, as will be more clearly apparent hereafter. Extending 75 through the gear housing 30 and transversely of the housing 28 is a bolt 37 having its head seated in a recess formed in the side of the housing and having a threaded end threaded into the housing 29 and engaged at its projecting end by a nut 38 by means of which it is held stationary within the gear housing. This bolt serves as a spindle on which is journaled a compound gear element comprising a sleeve 39 having 80 a worm 40 cut thereon positioned to engage with the annular worm gear 34 of the rack-engaging gear element heretofore described. At its opposite end, the sleeve 39 is provided with a spur gear wheel 41 positioned 85 in the lower portion of the housing 30.

The gear housing 30 is separate from the housing 29 and cover 28 of the gear casing and is held thereto by means of the bolt 37 and by the provision of an outward offset 90 42 in the cover 28, which offset part is provided with a toothed upper edge engaging with the toothed lower edge 43 of the housing 30. Within the upper portion of the housing 30 is journaled a second gear wheel 100 44 in mesh with the gear 41 in the lower portion of the casing 30, this gear 44 being suitably journaled within the housing 30 and having a hub 45 extending through a bore in the casing 30 and provided with a 105 squared aperture 46 therein.

Referring specifically to Fig. 13 of the drawings, it will be seen that the frame 1 is mounted upon the inside of the door jamb and that the gear case and its housings rest against the adjacent "buck" 47 which may be recessed to receive these gear housings. The space between the buck and jamb is, of course, covered by the usual strip of "trim" or molding 48. It is 110 through the gear 44 that motion is transmitted to the rack-engaging gear wheel 31 and through the rack of the operating bar to the transom. The appearance of the attachment is improved if the operating 115 handle, hereinafter described, which engages the squared aperture 46 of the hub 45, is centrally positioned with reference to the molding 48. This is possible by reason of the fact that the housing 30 may be 120 swung upon the bolt 37 as a pivot to position its hub 45 at the desired point, the bolt being first unscrewed and the housing pulled out sufficiently to clear its toothed edge 43 125 from the toothed edge of the offset 42. 130

When the hub 45 has been properly positioned relatively to molding 48, the housing 30 is pushed in to engage its toothed edge 48 with the teeth of the offset 42, and the bolt 5 37 then screwed in and its nut tightened.

It is further desirable to provide means for lubricating the parts of the gearing which are not easily accessible. In the specific form of gearing disclosed herein, such 10 parts will be particularly the gear element 40 and 34, the lubricant being distributed from these elements to the other gear elements. To this end I provide a bore in the door jamb 2 in alinement with the boss 33 of gear 31 through which boss, gear and 15 its sleeve 32 the lubricating aperture 35 extends, and insert into said bore in the boss 33, an oiling tube 49, to the outer end of which is secured a valve casing 50 having in 20 its outer end a lubricant inlet opening 51 normally closed by a ball valve 52 pressed thereagainst by a coiled spring 53. The outer end of this valved inlet to the lubricating tube is positioned at the door side of 25 the jamb 2, preferably slightly within the edge of the jamb so that access may be readily had thereto for the purposes of lubricating the gearing.

The molding strip 48 is, of course, provided with a suitably located bore through 30 which the spindle 54 of an operating handle 55 extends, a suitable rose 56 being preferably provided and resting against the outer face of the molding 48. The inner end of 35 the spindle 54 is squared and seats in the squared socket 46 of the hub of gear 44 so that when the handle is turned from the exterior, the worm gearing 34-40 is operated through gear train 44-41, operating 40 the rack and pinion gearing 25-31 to raise or lower the operating bar 18. All of the operating parts, except the transom arm 7 and operating handle 55, are concealed from view so that the appearance of the door or 45 other casing is not marred.

While I have herein described the bell-crank 20 and its connections as for a bottom hinged transom, it will, of course, be obvious that the specific manner of connection 50 may be modified to suit top and center hinged transoms, the same principles of operation being involved in each of these cases.

From the foregoing it will be obvious that the mechanism of the transom operator, except such parts as of necessity are directly connected to the transom itself, may be embodied in the form of an assembled unit mounted upon the frame or plate 1 ready for application to the jamb of a door. It 60 will also be obvious that the bell-crank lever 20 and the relatively eccentric lever formed by the arms 7 and 10 are so constructed and arranged to afford maximum leverage to raise the transom from lowered position, 65 and minimum leverage when the transom

is in closed position. In opening the transom, it is not necessary to employ any great amount of leverage, as the opening action is usually aided by gravity. On closing the transom, however, the greatest load is 70 encountered and I have so constructed and arranged the parts of my device that the maximum leverage is secured at the moment when it is most needed. It will also be evident that while the invention has been specifically described as applied to transoms, it is of general use in connection with various forms of hinged closures.

It should be understood that the arrangement of pin and slot connections shown may 80 be reversed without departing from the spirit or scope of this invention, since the function of the pin and slot connections shown at 6-8 and also at 11-23 is simply that of well-known compensating means and 85 is used to permit that degree of independent movement required in the type of compound or differential lever action shown.

While I have herein described and illustrated a specific embodiment of my invention, it should be understood that the same 90 may be altered in detail and relative arrangement of parts within the spirit of the invention and the scope of the appended claims.

What I claim, therefore, and desire to secure by Letters Patent is:

1. Operating means for swinging closures comprising a lever adapted for connection to and operation of a swinging closure, an actuating bell-crank lever pivoted adjacent one end and on a center different from that of said closure lever and operatively connected therewith to provide a varying leverage thereagainst progressively decreasing from 100 a maximum with the decrease from maximum of closure load on said closure lever, and manually controlled means for operating said bell-crank lever.

2. Operating means for swinging closures 110 comprising a lever adapted for connection to and operation of a swinging closure, an actuating bell-crank lever pivotally mounted adjacent one end and on a center different from that of said closure lever and having 115 an elongated slot between its apex and pivot point, said closure lever having a pin seating in said slot to move therein and relative to said pivot point, and manually controlled operating connections for the other end of 120 said bell-crank lever, whereby maximum leverage is secured through said bell-crank against said closure lever, said leverage progressively decreasing from maximum with the decrease of closure load on said closure 125 lever.

3. Operating means for swinging closures comprising a lever adapted for connection to and operation of a swinging closure, an actuating bell-crank lever pivotally mounted ad- 130

jacent one end and on a center different from that of said closure lever and having an elongated slot between its apex and pivot point, said closure lever having a pin seating 5 in said slot to move therein and relative to said pivot point, a movable operating bar, a link pivotally connecting said bar and the other end of said bell-crank lever; and manually controlled mechanism in operating connection with said bar and adapted to move the same to swing said bell-crank lever on its pivot, said bell-crank lever providing a leverage against said closure lever progressively decreasing from maximum with 10 the decrease from maximum of the closure load on said lever.

4. In a swinging transom operating means, an assembled unit construction comprising a carrier, a closure actuating means mounted thereon, a manually controllable operating mechanism spaced apart from said actuating means and also mounted on said carrier, and power transmitting means between said manually operable controllable means 20 and said actuating means.

5. In a concealed operating device for swinging transoms and the like, an assembled unit construction including a carrier, a transom actuating lever pivotally mounted 30 on said carrier, manually controllable operating means also mounted on said carrier and spaced apart from said lever, a power transmitting means operatively connecting said manually controllable operating means 35 and said lever.

6. In operating means for swinging closures, a unit comprising a frame, a closure-

actuating lever pivotally carried thereby at one end and having an elongated slot therein adjacent its pivotal end, an operating rod 40 on said frame movable relative thereto and in operative connection with the other end of said lever, and a manually controlled and operable gear carried by said frame and in operative connection with said rod. 45

7. In operating means for swinging closures, a unit comprising a frame, a bell-crank lever pivotally carried thereby at one end and having an elongated slot therein between its apex and its pivoted end, an operating rod guided by and movable relative to the frame and provided with a rack, a pivoted link operatively connecting said rod to the other end of said lever, and a gear train mounted upon said frame adapted for 50 manual actuation and in operative connection with said rod rack.

8. Operating means for swinging closures comprising a frame, a lever adapted for connection to and operation of a swinging closure and journaled in said frame, a closure-actuating lever pivotally mounted on said frame adjacent one end and having an elongated slot therein adjacent its pivotal end in operative connection with said closure lever, an operating rod on said frame and in operative connection with said pivoted actuated lever, and manually controlled mechanism mounted on said frame and in operative connection with said rod. 60
